REFRIGERATING APPARATUS

Raymond E. Tobey, Springfield, Mass., assignor to
Westinghouse Electric & Manufacturing Com-
pany, East Pittsburgh, Pa., a corporation of
Pennsylvania

Application May 11, 1938, Serial No. 207,247

17 Claims. (Cl. 62—4)

My invention relates to refrigerating apparatus and has for an object to provide improved apparatus of this kind.

A further object of the invention is to maintain the temperature within a refrigerated zone substantially constant irrespective of changes in temperature exteriorly of the zone, which temperature changes vary the amount of heat leakage into the zone.

It is a further object of the invention to vary the operation of a refrigerating mechanism in response to variations in temperature of the ambient atmosphere so that the temperature of the refrigerated zone is maintained substantially constant.

It is a further object of the invention to maintain the temperature differential of the refrigerant evaporator and the temperature of the air cooled thereby within closer limits than has been effected heretofore.

It is a still further object of the invention to control the operation of a refrigerating machine by a thermostat subjected to the temperature of the high pressure condensed refrigerant prior to its admission into the evaporator structure and, furthermore, to subject the thermostat to the temperature of the low pressure condensed refrigerant prior to its admission into the evaporator.

These and other objects are effected by my invention as will be apparent from the following description and claims taken in connection with the accompanying drawing, forming a part thereof, in which:

Fig. 1 is a diagrammatic view of a refrigerating machine constructed and arranged in accordance with my invention;

Figs. 2 and 3 are respective side and end views of an element of the control apparatus employed in Fig. 1;

Figs. 4 and 5 are respective side and end views of a modified form of control element shown in Figs. 2 and 3; and

Fig. 6 is a side view of another form of the control element applied to a conventional evaporator.

Referring now to Fig. 1 of the drawing, I have shown my invention applied to a refrigerator of the domestic type, including an insulated cabinet structure 10 that encloses a compartment or zone 11 to be refrigerated. Heat is abstracted from the air in the zone 11 by means of an evaporator 12 of conventional sheet metal construction which includes an inlet conduit 13 for condensed refrigerant and an outlet conduit 14 for refrigerant vaporized in the evaporator.

Circulation of refrigerant through the evaporator is effected by a refrigerating machine, generally indicated at 15, which preferably operates on the compressor-condenser-expander cycle. The refrigerating machine 15 includes a compressor 16, driven by an electric motor 17. A condenser 18 is cooled by the ambient air which is circulated by a fan 19. Refrigerant vaporized in the evaporator 12 is withdrawn therefrom through the conduit 14 by the compressor 16 and is compressed to a relatively high pressure. The compressed refrigerant is delivered to the condenser 18 through a conduit 21. Refrigerant liquefied in the condenser 18 is conveyed to the inlet conduit 13 of the evaporator through a suitable expansion device, such as, for example, a capillary tube 22. The capillary tube 22 operates to reduce the relatively high pressure of the 20 condensed refrigerant to the pressure maintained in the evaporator 12 by the compressor 16, as is well understood.

The capillary tube 22 includes an elongated passage of fixed flow area (not shown) which 25 restricts the flow of refrigerant and effects a reduction in the pressure thereof. The inlet of the tube 22 may be connected to the condenser by a conduit 20 as shown.

As described hereinafter, the refrigerating machine 16 is controlled thermostatically to maintain the temperature of the evaporator 12 at predetermined values that are adjusted by changes in the temperature of the ambient atmosphere exteriorly of the zone 11. The compensation is such that the mean temperature of the evaporator 12 varies inversely with changes in the temperature of the ambient atmosphere. The different rates of heat leakage into the zone 11 caused by ambient temperature changes are, 40 therefore, compensated for by various rates of heat absorption effected by the evaporator 11.

Preferably, a thermostat of the expansible-fluid type, shown generally at 23, is employed for controlling operation of the compressor 16. The thermostat 23 includes an expansible bellows 24 connected by a tube 25 with a bulb 26, which elements define a closed chamber for an expansible fluid. Preferably, a volatile fluid whose pressure is a function of the temperature of the bulb 26 is employed. The thermostat 23 includes a pivoted arm 27 that is actuated by the bellows 24 and biased by a spring 28. The arm 27 operates a switch 29, preferably by means of a snap-acting mechanism 31, so that the switch 29 is opened

and closed, respectively, in response to predetermined low and high pressures in the bellows 24 and, therefore, predetermined low and high temperatures of the bulb 26. An adjustment 30 may be provided for varying the bias of the spring 28 and, therefore, the temperatures of the bulb 26 at which opening and closing of the switch 29 are effected. The switch 29 controls energization of the motor 17 that is connected to an electric circuit L₁—L₂. As the construction and operation of adjustable fluid type thermostats are well understood in the art, further description of the same is deemed unnecessary.

In the copending application of Leslie B. M. Buchanan, Serial No. 122,505, filed January 27, 1937, and assigned to the assignee of the present application, there is disclosed and claimed a refrigerating system of the type set forth heretofore wherein the mean temperature of the evaporator is varied inversely in response to ambient temperature changes. In this application, the thermal responsive element of the control responds to the temperature of the refrigerant in the evaporator and is disposed in heat transfer relation with the condensed refrigerant admitted to the capillary tube, the temperature of the condensed refrigerant being a function of ambient temperature. As the flow of condensed refrigerant substantially ceases during inactive periods of the machine, the compensation effected by the condensed refrigerant prevails only during active periods of the machine and, therefore, it is only the "cut off" temperature of the evaporator, i. e., the temperature at which the compressor is stopped, which is effected by ambient temperature changes. The present invention defines an improvement of the system claimed in said copending application in that both the "cut off" and "cut on" temperatures of the evaporator are varied as the outside or ambient temperature varies. The "cut on" temperature is the temperature of the bulb at which the compressor is started.

In practicing the present invention, the thermostatic bulb 26 is secured to a member 33 of metal or other heat conducting material, which member 33 may be disposed in the zone 11. The member 33 is disposed in heat transfer relation with the low temperature refrigerant in the evaporator 12 and with the condensed refrigerant in the inlet end of the capillary tube 22, the temperature of the latter being a function of outside temperature. Preferably, the member 33 is connected to the inlet conduit 13 of the evaporator, which is of low heat storage capacity compared to the main body of the evaporator and, therefore, responds more quickly to changes in the temperature of the refrigerant therein. Obviously, other portions of the evaporator 12 may be connected to the member 33 if desired. The tube 22 and the bulb 26 may be secured to the member 33 by a clamp 34 and the inlet conduit 13 of the evaporator may be soldered or otherwise secured to the member 33 in proximity to the bulb 26 as shown in Figs. 2 and 3.

During active periods of the apparatus, heat is transferred to the member 33 and the control bulb 26 from the condensed refrigerant in amounts varying with the temperature of the ambient atmosphere. Heat is abstracted from the member 33 and the control bulb 26 by the low temperature refrigerant in the evaporator inlet conduit 13. When the outside temperature is relatively high, heat is imparted to the member 33 and bulb 26 at a relatively high rate so that

the compressor must operate to depress the temperature of the evaporator 12 to a relatively low value before the control bulb 26 is cooled sufficiently to terminate operation of the compressor. When the outside temperature is relatively low, less heat is imparted to the member 33 and control bulb 26 so that the latter is cooled to the temperature at which it terminates operation of the compressor when the evaporator temperature is at a higher value.

While the temperature of the portion of the member 33 in contact with the bulb 26 is substantially the same as the bulb temperature, the average temperature of the member 33 as a whole and the amount of heat stored therein are higher when the outside temperature is high than when the outside temperature is low. Heat, therefore, is continuously imparted to the bulb 26 by the member 33, the rate of heat transmission varying with the average temperature of the member 33, and, therefore, the temperature of the exterior atmosphere.

During inactive periods of the compressor, the supply of heat to the member 33 is terminated as the flow of condensed refrigerant ceases. The temperatures of the evaporator 12 and the control bulb 26 increase due to the heat load in the zone 11. The member 33 which has stored heat during the operating period of the compressor imparts heat to the control bulb 26 and assists in raising its temperature. Accordingly, when the temperature of the member 33 is high due to a high ambient temperature, the control bulb 26 will be heated to its "cut on" temperature sooner than when the temperature of the member 33 is low or when the ambient temperature is low. Accordingly, both the "cut on" and "cut off" temperatures of the evaporator 12 vary with variations in the ambient temperature.

The control bulb 26 is disposed contiguous to the evaporator inlet conduit 13 and responds to both the temperatures of said conduit and the member 33. The temperature of the member 33 is affected by the temperatures of the evaporator conduit 13 and the capillary tube 22. The member 33 defines a heat storage body which imparts more or less heat to the control bulb 26 during inactive periods of the machine, depending upon the temperature of the outside atmosphere. It will be understood that operation of the compressor 16 is started and stopped when the temperature of the bulb 26 attains predetermined values, which values are determined by the position of the adjustment 30 and bias of the spring 28. The temperatures of the bulb 26 at which the compressor is started and stopped are the same for a given position of the adjustment 30 regardless of the ambient temperature.

My improved control apparatus provides compensation for varying heat loads in the zone 11 due to periodic opening of the access door thereof or to varying amounts of heat in the articles to be cooled. As the member 33 and control bulb 26 are subjected to the air in the zone 11, their temperatures are affected by the temperature of the air. As the temperature of the air in the zone 11 increases due for example, to the insertion of relatively warm products therein, the rate of heat flow to the bulb 26 and conduit 13 increases so that the rise in the temperature of the bulb 26 to the "cut on" value is expedited. Accordingly, the control bulb 26 is affected by the temperature of the cooled air in addition to the temperatures of the liquid conduit 13 and the capillary tube 22.

Operation

As shown in Fig. 1, the refrigerant condensing unit 15 is inactive as the temperature of the bulb 26 is below the value at which it effects closing of the thermostatic switch 29. When the temperature of the bulb 26 is increased to a predetermined value, for example, 35° F., the thermostatic switch 29 is closed and operation of the condensing unit 15 is initiated. Translation of vapor from the evaporator 12 to the condenser 18 is therefore effected by the compressor 16. The pressure within the condenser 18 rapidly increases to a value at which condensation is effected. The condensed refrigerant passes from the condenser 18 through the conduit 20 and capillary tube 22 to the evaporator inlet conduit 13. The pressure within the condenser 18 rapidly increases to a value at which condensation is effected. The condensed refrigerant passes from the condenser 18 through the conduit 20 and capillary tube 22 to the evaporator inlet conduit 13.

The temperature of the refrigerant entering the capillary tube 22 bears a direct relation to the temperature of the ambient atmosphere and imparts heat to the heat storage member 33 and the thermostatic bulb 26 at a rate determined by the ambient temperature. The temperature of the evaporator inlet conduit 13 is rapidly depressed subsequent to the starting of the condensing unit 15 and heat is abstracted thereby from the member 33 and thermostatic bulb 26. When the temperature of the ambient atmosphere is relatively low, for example, 65° F., the amount of heat imparted to the member 33 is relatively low. Accordingly, the cold evaporator conduit 13 depresses the temperature of the bulb 26 in a relatively short period of time to the value, for example, 20° F., at which the thermostatic switch 29 is opened, so that the compressor runs only a short time. Accordingly, the refrigerating temperature of the evaporator at the time the compressor is stopped is relatively high in a 65° ambient atmosphere.

During the inactive period of the condensing unit 15, the temperature of the bulb 26 is increased due to the heat load in the box and to a relatively small amount of heat which is imparted thereto by the member 33, which heat has been stored in the member 33 during the active period of the compressor. When the temperature of the bulb 26 has attained a value of 35° F., the switch 29 is closed and circulation of refrigerant is initiated.

It will be assumed that the temperature of the ambient atmosphere increases to a value of, for example, 110° F. The operation of the apparatus is similar to that described heretofore, that is, the compressor is started and stopped when the thermostatic bulb temperature is 35° F. and 20° F., respectively. However, during operating periods, heat is imparted to the member 33 at a high rate by the condensed refrigerant so that the temperature of the evaporator 12 and its conduit 13 must be depressed to a relatively low value by longer operation of the compressor 16 in order to abstract sufficient heat from the bulb 26 to depress its temperature to the cut off value of 20° F. The temperature of the evaporator 12 at the time of starting the compressor is also lower than when the ambient temperature is low because of the more rapid heating of the bulb 26 to its "cut on" temperature by the member 33, it being understood that the temperature of the member 33 and the amount of heat stored therein are relatively high when the ambient temperature is high.

Accordingly, the temperatures of the evaporators at the time of both starting and stopping

of the compressor are lower when the outside temperature is high than when the outside temperature is low. The system, therefore, operates to maintain a substantially constant temperature differential, while increasing and decreasing the mean evaporator temperature. This result I obtain by employing a heat storage member of suitable mass having the thermostatic element secured thereto, which member is heated and cooled by the condensed and evaporated refrigerant, respectively.

As set forth heretofore, the control bulb 26 is affected by varying temperatures of the air in the compartment 11 due to different heat loads. The insertion of a relatively warm article to be refrigerated in the compartment 11 increases the air temperature, which change is reflected by the conduit 13 and control bulb 26 prior to the change in temperature of the body of the evaporator 12. Accordingly, by connecting the bulb 26 to a portion of the evaporator of low heat storage capacity, changes in temperature of the evaporator 12 due to varying heat loads are anticipated by the control bulb 26.

The compensating effect produced by the capillary tube may be varied by releasing the clamp 34 and adjusting either the control bulb 26 relative the evaporator inlet conduit 13 or the capillary tube 22 relative the control bulb 26. In either event, the effect of the capillary tube in heating the bulb 26 is varied and, therefore, the compensating effect produced by the tube 22 is varied.

In Figs. 4 and 5, a second embodiment of the invention is disclosed wherein a heat storage member 41 is provided having a slot 42 formed therein. The evaporator inlet conduit 13 is soldered or otherwise affixed to the member 41 within the slot 42. A separate plate 43 is secured to the member 41 by a screw 44 which plate 43 has the capillary tube 22 soldered or otherwise secured thereto. The control bulb 26 is clamped between the plate 43 and the member 41 and responds to the temperature of both of these elements. The operation of the refrigerating apparatus employing either of the embodiments is similar.

A third embodiment of the invention is shown in Fig. 6 wherein a heat storage member 45 is secured directly to an evaporator 46. The capillary tube 22 and control bulb 26 are secured to the member 45 in any suitable manner, such as, for example, by soldering. The member 45 is provided with one or more slots 47, within which screws 48 are disposed, which screws 48 are threaded in the evaporator structure 46. Adjustment of the member 45 and, therefore, the bulb 26 relative to the evaporator 46 is provided by the sliding connection between the member 45 and the evaporator 46. Accordingly, if the capillary tube is overcompensating, the member 45 and bulb 26 may be moved closer to the evaporator 46 so that the control bulb 26 is cooled more rapidly. Conversely, if the capillary tube is under-compensating, the control bulb 26 is moved away from the evaporator so that heat from the capillary tube has greater effect in warming the control bulb and effects lower evaporator temperatures at the time the compressor is started and stopped.

From the foregoing description, it will be apparent that I have provided improved refrigerating apparatus wherein compensation for different rates of heat leakage into the refrigerated zone due to varying temperatures exteriorly of the refrigerated zone is provided. The mean

- temperature of the evaporator is varied inversely with outside temperature changes while maintaining the temperature differential of the evaporator at a substantially constant value. Furthermore, the control apparatus readily responds to variations in the heat load in the refrigerated zone whereby the temperature of the evaporator is adjusted to compensate for said variation in an anticipating manner.
- 10 While I have shown my invention in several forms, it will be obvious to those skilled in the art that it is not so limited, but is susceptible of various other changes and modifications without departing from the spirit thereof, and
- 15 I desire, therefore, that only such limitations shall be placed thereupon as are imposed by the prior art or as are specifically set forth in the appended claims.
- What I claim is:
- 20 1. In refrigerating apparatus, the combination of means defining a zone to be refrigerated, an evaporator for abstracting heat from said zone, means for circulating refrigerant through the evaporator, a heat storage member, means for imparting heat to a portion of said member in response to changes in temperature of the air exteriorly of said zone, means for abstracting heat from a second portion of said member in response to the temperature of the evaporator and means responsive to the temperature of a portion of the heat storage member for controlling the operation of the refrigerant circulating means.
- 25 2. In refrigerating apparatus, the combination of refrigerant condensing and evaporating means, means for circulating refrigerant through the condensing and evaporating means, means for passing air in heat transfer relation with the condensing means for abstracting heat from the latter, whereby the temperature of the condensed refrigerant is a function of the air temperature, a heat storage member disposed in heat transfer relation with both the condensed refrigerant and the refrigerant in the evaporator, and means responsive to the temperature of a portion of said member for controlling the operation of the circulating means.
- 30 3. In refrigerating apparatus, the combination of a refrigerant evaporator, a condenser, means for translating air over the condenser for cooling the same, means for translating refrigerant vaporized in the evaporator to the condenser for liquefaction, means having an elongated passage of fixed flow area for conveying the condensed refrigerant from the condenser to the evaporator, a heat storage member disposed in heat transfer relation with the last-mentioned means and with the refrigerant in the evaporator, and means responsive to predetermined high and low temperatures of the heat storage member for initiating and terminating operation of the refrigerant translating means.
- 35 4. The combination as claimed in claim 3 including means for varying the rate of transfer of heat between the condensed refrigerant conveying means and the heat storage member.
- 40 5. In refrigerating apparatus, the combination of refrigerant condensing and evaporating means, means for circulating refrigerant through the condensing and evaporating means, means for passing air in heat transfer relation with the condensing means for abstracting heat from the latter, whereby the temperature of the condensed refrigerant is a function of the air temperature, a heat storage body disposed in

heat transfer relation with both the condensed refrigerant and the refrigerant in the evaporator, means for varying the rate of transfer between the heat storage member and one of said bodies of refrigerant and means responsive to the temperature of the heat storage body for controlling the operation of said refrigerant circulating means.

6. In refrigerating apparatus, the combination of means defining a zone to be cooled, a refrigerant evaporator for abstracting heat from said zone, means for withdrawing vaporous refrigerant from the evaporator, a condenser for liquefying the withdrawn refrigerant, means for translating air exterior of said zone in heat transfer relation with the condenser for abstracting heat from the same, whereby the temperature of the condensed refrigerant varies with variations in the temperature of said air, a capillary tube for conducting condensed refrigerant from the condenser to the evaporator, a heat conducting member disposed in heat transfer relation with a portion of the capillary tube whereby heat is imparted to the member at rates varying with the temperature of said exterior air, said member being disposed in heat transfer relation with the refrigerant in the evaporator whereby heat is abstracted from the member at rates varying with the temperature of the evaporator, and means responsive to the temperature of a portion of the heat conducting member for controlling the operation of the refrigerant withdrawing means.

7. In refrigerating apparatus, the combination of means defining a zone to be cooled, a refrigerant evaporator for abstracting heat from said zone, means for withdrawing vaporous refrigerant from the evaporator, a condenser for liquefying the withdrawn refrigerant, means for translating air exterior of said zone in heat transfer relation with the condenser for abstracting heat from the same, whereby the temperature of the condensed refrigerant varies with variations in the temperature of said air, an expansion device having an elongated passage of fixed flow area for conveying condensed refrigerant from the condenser to the evaporator, a heat conducting member disposed within said zone and in heat transfer relation with a portion of the expansion device adjacent the inlet end thereof whereby heat is imparted to said member at rates varying with the temperature of said exterior air, said member being disposed in heat transfer relation with the refrigerant in the evaporator whereby heat is withdrawn from the member at rates varying with the temperature of the evaporator, and means responsive to the temperature of the heat conducting member for controlling the operation of the refrigerant withdrawing means.

8. In refrigerating apparatus, the combination of means defining a zone to be cooled, a refrigerant evaporator for abstracting heat from said zone, means for withdrawing vaporous refrigerant from the evaporator, a condenser for liquefying the withdrawn refrigerant, means for translating air exteriorly of said zone in heat transfer relation with the condenser for abstracting heat from the same, whereby the temperature of the condensed refrigerant varies with variations in the temperature of said air, an expansion device having an elongated passage of fixed flow area for conveying condensed refrigerant from the condenser to the evaporator, a heat conducting member disposed in heat transfer relation

with a portion of the expansion device adjacent the inlet end thereof whereby heat is imparted to said member at rates varying with the temperature of said exterior air, said member being disposed in heat transfer relation with a portion of the evaporator, whereby heat is withdrawn from the member at rates varying with the temperature of the evaporator, means for adjusting the expansion device relative to the member, and

10 means responsive to the temperature of the member for controlling the operation of the refrigerant withdrawing means.

9. In refrigerating apparatus, the combination of means defining a zone to be cooled, a refrigerant evaporator for abstracting heat from said zone, means for withdrawing vaporous refrigerant from the evaporator, a condenser for liquefying the withdrawn refrigerant, means for translating air exterior of said zone in heat transfer relation with the condenser for abstracting heat from the same, whereby the temperature of the condensed refrigerant varies with variations in the temperature of said air, an expansion device having an elongated passage of fixed flow area for conveying condensed refrigerant from the condenser to the evaporator, a heat conducting member disposed within said zone and in heat transfer relation with a portion of the expansion device adjacent the inlet end thereof, said member being disposed in heat transfer relation with the evaporator, means for adjusting the member relative to the evaporator whereby the rate of heat transfer therebetween is varied, and means responsive to the temperature of the heat conducting member for controlling the operation of the refrigerant withdrawing means.

10. In refrigerating apparatus, the combination of means defining a zone to be cooled, a refrigerant evaporator for abstracting heat from said zone, means for withdrawing vaporous refrigerant from the evaporator, a condenser for liquefying the withdrawn refrigerant, means for translating air exterior of said zone in heat transfer relation with the condenser for abstracting heat from the same, whereby the temperature of the condensed refrigerant varies with variations in the temperature of said air, a capillary tube for conveying condensed refrigerant from the condenser to the evaporator, a heat conducting member disposed within said zone and in heat transfer relation with a portion of the capillary tube adjacent its inlet end, whereby heat is imparted to said member at rates varying with the temperature of said exterior air, said member being disposed in heat transfer relation with a portion of the evaporator, whereby heat is withdrawn from the member at rates varying with the temperature of the evaporator, thermostatic means for controlling the operation of the refrigerant withdrawing means and including a thermal responsive element disposed in heat transfer relation with the heat conducting member, and means for adjusting the thermal responsive element relative to the heat conducting member.

11. In refrigerating apparatus, the combination of means defining a zone to be cooled, an evaporator for abstracting heat from said zone, and including an inlet conduit for liquid refrigerant, a condenser, means for passing air exteriorly of said zone in heat transfer relation with the condenser for cooling the same whereby the temperature of the condensed refrigerant varies with variations in temperature of the air, and means for translating vaporous refrigerant from

the evaporator to the condenser for liquefaction therein, a capillary tube for conveying the condensed refrigerant from the condenser to said evaporator inlet conduit, a member disposed in heat transfer relation with the evaporator inlet conduit and the inlet end of said capillary tube whereby heat is abstracted from the member at rates varying with the temperature of the refrigerant in the evaporator and heat is imparted to the member at rates varying with the temperature of the liquid refrigerant in the condenser, and means for controlling the operation of the refrigerant translating means in response to the temperature of said member.

12. In refrigerating apparatus, the combination of means defining a zone to be cooled, an evaporator for abstracting heat from said zone and including a portion of relatively small heat storage capacity spaced therefrom, means for condensing refrigerant vaporized in the evaporator, a heat conducting member in heat transfer relation with said evaporator portion and a thermostat for controlling the operation of the refrigerant condensing means and including a thermal responsive element disposed in heat transfer relation with said heat conducting member, and means for imparting heat to said thermal responsive element in amounts varying with the temperature of the atmosphere exteriorly of said compartment.

13. In refrigerating apparatus, the combination of means defining a zone to be cooled, an evaporator for abstracting heat from said zone, means for condensing at relatively high pressure refrigerant vaporized in the evaporator at relatively low pressure, a thermostat for controlling the operation of the refrigerant condensing means and including a thermal responsive element spaced from the evaporator and responsive to the temperature thereof, and means for imparting heat to said thermal responsive element other than through the medium in the zone to be cooled and in amounts varying with the temperature of the atmosphere exteriorly of the refrigerated zone.

14. In refrigerating apparatus, the combination of means defining a zone to be cooled, an evaporator for abstracting heat from said zone, means for condensing at relatively high pressure refrigerant vaporized in the evaporator at relatively low pressure and a thermostat for controlling the operation of the refrigerant condensing means and including a thermal responsive element, said thermal responsive element being disposed in heat transfer relation with the high pressure and low pressure condensed refrigerant prior to its admission to the evaporator.

15. In refrigerating apparatus, the combination of means defining a zone to be cooled, an evaporator for abstracting heat from said zone, means for condensing at relatively high pressure refrigerant vaporized in the evaporator at relatively low pressure, means for conveying the condensed refrigerant from the condenser to the evaporator and including means for reducing the pressure of the refrigerant from its condensing pressure to its pressure of vaporization and a thermostat for controlling the operation of the condensing means and including a thermal responsive element, said refrigerant conveying means being disposed in heat transfer relation with the thermal responsive element so that heat is transferred between the thermal responsive element and the high and low pressure condensed refrigerant prior to the admission of the condensed refrigerant to the evaporator.

16. In refrigerating apparatus, the combination of means for defining a zone to be refrigerated, an evaporator for abstracting heat from the media in said zone and including a portion of relatively small mass, means for circulating refrigerant through the evaporator, a thermostatic device for controlling the operation of the circulating means and including a heat-responsive element disposed in heat transfer relation with the media in said zone, and a heat-conducting member connecting said device and the portion of the evaporator of relatively small mass for conducting heat therebetween.
17. In refrigerating apparatus, the combination

tion of means for defining a zone to be refrigerated, cooling means for abstracting heat from the media in said zone and having associated therewith a portion of relatively small mass, means for circulating refrigerant through the cooling means, a thermostatic device for controlling the operation of the circulating means and including a heat responsive element disposed in heat transfer relation with the medium in said zone and a heat conducting member connecting said device and the portion of the cooling means of relatively small mass for conducting heat therebetween.

RAYMOND E. TOBEY.
